UNITED STATES PATENT OFFICE.

JAMES M. CHAMBERS, OF ST. LOUIS, MISSOURI.

BARREL-HEATER.

SPECIFICATION forming part of Letters Patent No. 783,819, dated February 28, 1905.

Application filed November 28, 1904. Serial No. 234,671.

To all whom it may concern:

Be it known that I, JAMES M. CHAMBERS, a citizen of the United States, residing at St. Louis, Missouri, have invented a certain new and useful Improvement in Barrel-Heaters, of which the following is a full, clear, and exact description, such as will enable others skilled in the art to which it appertains to make and use the same, reference being had to the accompanying drawings, forming part of this specification, in which—

Figure 1 is a vertical longitudinal sectional view through a barrel-heater constructed in accordance with my invention. Fig. 2 is a cross-sectional view on the line 22 of Fig. 1, and Fig. 3 is a cross-sectional view on the line 33 of Fig. 1.

This invention relates to barrel-heaters, and is particularly designed for heating and drying casks or barrels preparatory to hooping and finishing the same.

One of the objects of the invention is to heat the barrel or cask externally and internally, so as to obviate the necessity and inconvenience of lifting the barrel by hand for placing it around the heater.

Another object of the invention is to provide means whereby a maximum heat efficiency will be generated by a given amount of fuel, so that the products of combustion will have an opportunity to generate considerable heat before passing off through the chimney or into the outside atmosphere when it leaves the heater.

Another object of the invention is to provide means whereby a hanging fire-pot or grate may be suspended within the heater in such a manner that the draft will pass through the grate from the top and then be deflected upwardly by a suitable baffle, so that the products of combustion may act upon the surrounding casing which is to be heated.

Other objects and advantages, as well as the novel details of construction of this invention, will be specifically described hereinafter, it being understood that changes in form, proportion, and minor details of construction may be resorted to without departing from the spirit or sacrificing any of the advantages thereof.

In the preferred form of my invention as illustrated in the accompanying drawings I utilize a plurality of standards 1, which may consist of castings, channel-irons, or any other suitable construction and which support a drum or sheet-iron casing 2. This casing rests on top of a ring 3 on the standards, and upon the upper edge of the drum is a cover 4, secured to the ring 3 by the tie-rods 5. The cover 4 is provided with a central opening 6 surrounded by a depending circular flange 6, extending within the casing 2 and having an inwardly-projecting lug 7 at its lower edge, which is in a lower but a parallel plane to the plane of the cover 4. It will be seen that the lug 7 projects inwardly at a right angle to the flange 6 and constitutes a rest to support the hanging fire-pot 8, which is flared downwardly from its upper end to a point at its opposite end 9, said fire-pot having a depending circular baffle 10 integral therewith, the purpose of which will be apparent as the construction of the invention is better understood. The fire-pot 8 constitutes a receiver for the fuel, and at its lower end 9 are inwardly-projecting lugs 11, divided by spaces 12, whereby the outwardly-projecting lugs 13 of the grate 14 may be caused to alternate with the lugs 11, and by slightly rotating the grate 14 the lugs 13 will be caused to register with those designated by the numeral 11, whereby the grate 14 will be hung or suspended from the fire-pot 8. The grate 14 is open at its top and is provided with a plurality of vertical bars 15 and transverse bottom bars 16, so that the draft through the fuel will in no wise be retarded.

Suspended from the flange 6 is a sheet-iron inner casing 17, which entirely surrounds the fire-pot, grate, and baffle and projects below the lower edge of said baffle 10. This sheet-iron inner casing 17 is provided at its lower edge with an inwardly-projecting flange 18, the inner edge of which surrounds an opening normally closed by a cover 19, having a lug 20 at one edge thereof and a swinging locking device 21 at the opposite edge, so that the lug 20 and the locking device 21 may be caused to engage the flange 18, so as to support the cover 19 on said flange.

The top 22 of the heater is bolted or otherwise secured to the cover 4, and it is provided with a depending flange 23, extending within the opening surrounded by the flange 6, the 5 flange 23 being substantially parallel with the flange 6 and having outwardly-projecting flange 24 resting on the upper lug 25 of the fire-pot 8, to which said flange 24 is bolted. It will be observed that the flange 23 is substantially 10 the same diameter as the entrance-opening of the fire-pot 8, so that the fuel will be conveniently guided into the fire-pot 8, constituting the fuel-receiver, and into the grate.

15 A swinging cover 26 is pivoted to the top 22 of the heater, whereby the opening 27 may be uncovered for the introduction of fuel or to regulate the drafts.

In the top 22 and surrounded by the flange 20 28 is a smoke-opening 29, which communicates with a space 30, formed by the outer walls of the fire-pot 8 and the wall of the casing 17.

Between the outer casing 2 and the inner 25 casing 17 are the vertical rods 31 of the elevating device, including the base or platform 32, supported by said rod, and on which the barrel or cask is placed. These rods are connected at their tops by the cross-bar 33, and 30 intermediate the ends of the cross-bar is a pulley 34.

From a suitable support 35 is a cord or cable 36, passing around the pulley 34, thence over a pulley 37, and on the end of this cord 35 or cable 36 is a counterbalance-weight 38 of about the same weight as the cask or barrel to be heated.

In operation it is to be assumed that fire is in the grate 14 and that the barrel has been 40 placed upon the platform 32. The draft will enter through the top of the fire-pot, as indicated by the arrows, and pass down through the grate 14 to the bottom of the inner casing 17, where it will be deflected by the cover 19 45 and the baffle 10 in an upward direction through the space 30 and between the baffle 10 and the inner casing 17 until it passes through the smoke-opening 29. Thus the entire inner casing 17 will be heated and will 50 radiate heat into the space 39 formed between the inner and outer casings and in which the barrel will rest. The operator may cause the counterbalance-weight 38 to descend and in an obvious manner raise the barrel 40 until it 55 surrounds the inner casing and is in turn surrounded by the outer casing. Thus it will be apparent that the outer and inner walls of the barrel will be efficiently heated preparatory to hooping and finishing.

60 One of the particular advantages resulting from the construction hereinabove described is that the downdraft will permit an even heat to radiate from the inner casing of the heater, so that a uniform drying out will take place

from one end of the barrel to the other. An- 65 other advantage is that the exterior of the barrel will also be thoroughly dried. When it is desired to rake the grate, this can be readily accomplished by removing the cover 19, so that access to the grate 14 may be easily 70 had. By suspending the grate as indicated in the drawings the grate may be easily removed, as well as the entire fire-pot may be taken out or assembled. The arrangement and construction of the grate is such that an easy combustion 75 of the fuel is insured and the draft will be in no wise retarded. Therefore the maximum efficiency for the device will be provided.

Having thus described my invention, what 80 I claim, and desire to secure by Letters Patent, is—

1. A barrel-heater comprising an inner and outer casing, a hanging grate in the inner casing, and a baffle surrounding the grate and extending nearly to the bottom of the inner casing; substantially as described.

2. A barrel-heater comprising an inner and outer casing, a grate within the inner casing, a baffle surrounding the grate and depending 90 below the same, said baffle being spaced from the walls of the inner casing, and means for directing a downdraft through the grate and between the baffle and the inner casing; substantially as described.

3. A barrel-heater comprising a casing, a fire-pot within the casing and having an entrance-opening at its upper end, a grate suspended from the fire-pot, a baffle depending from the fire-pot and surrounding the grate, 100 said baffle being spaced from the inner walls of the casing, and a cover at the top of the casing provided with a smoke-pipe opening; substantially as described.

4. A barrel-heater comprising a casing, a 105 cover for the casing having a depending flange, a fire-pot suspended from said flange, a grate hanging in said fire-pot, a cylindrical baffle depending from the fire-pot and surrounding the grate, said baffle terminating at a point 110 above the bottom of said casing, and a removable cover for closing an opening in the bottom of said casing; substantially as described.

5. A barrel-heater comprising an inner and outer casing, a cover for the outer casing and 115 having depending flanges partially forming the walls of the inner casing, a sheet-metal cylinder depending from said flanges and constituting the remaining walls of the inner casing, lugs carried by said flanges, a fire-pot suspended from said lugs, a grate hanging in the fire-pot, a top having depending flanges extending to the upper edge of the fire-pot and provided with closing means, and a removable cover for closing an opening in the bottom of the casing; substantially as described.

6. A barrel-heater comprising an inner and outer casing, a fire-pot within the inner cas-

ing, a grate suspended therefrom, a baffle depending from the fire-pot and surrounding the grate whereby a downdraft-flue is provided and an updraft-flue is also provided, and means 5 for elevating a cask to a position between the walls of the inner and outer casings; substantially as described.

In testimony whereof I hereunto affix my signature, in the presence of two witnesses, this 12th day of November, 1904.

JAMES M. CHAMBERS.
